UNITED STATES PATENT OFFICE.

BERNADOTTE BIXBY, OF LOS ANGELES, CALIFORNIA.

BUCKLE.

No. 878,764.

Specification of Letters Patent.

Patented Feb. 11, 1908.

Application filed August 7, 1906. Serial No. 329,610.

To all whom it may concern:

Be it known that I, BERNADOTTE BIXBY, a citizen of the United States, residing at Los Angeles, county of Los Angeles, State of California, have invented and discovered a new and useful Improvement in Buckles; and I do hereby declare the following to be a clear, full, and exact description of the invention, such as will enable others skilled in the art to which it appertains to make and use the same.

This invention relates to improvements in buckles for clothing and for other purposes; and the objects of my improvement are, first to construct buckles to be used upon trousers, vests and other garments made by clothiers and tailors, having the prongs thereof guarded to avoid pricking the fingers of persons adjusting the buckles to the garments and of persons wearing apparel to which the buckles are fastened; and second, and to place upon the market buckles provided with means for preventing the prongs thereof from piercing and tearing the wearing apparel contiguous to the buckles upon the bodies of persons using my improvement.

The invention consists essentially in the construction, combination and arrangement of the several parts as will be hereinafter fully described in the specification, shown upon the drawings appended hereto and specifically pointed out in the claims made a part hereof.

I attain these objects by the construction and arrangement of the several parts illustrated upon the accompanying drawings, in which—

Figure 1 is a plan view of my improvement showing the buckle frame and the prong-bar and prongs behind the guards; Fig. 2 is a plan view of my improved buckle showing the prongs thereof removed from under and from behind the guards; and Fig. 3 is a sectional view taken upon the line $b-b$ of Fig. 1 of the drawings looking in the direction of the arrows.

Similar reference numerals, letters and characters refer to like parts throughout the several views of the drawings.

The reference numeral 1, denotes the frame of the buckle desirably made of one piece and preferably stamped out of sheet iron or other suitable material.

The reference numeral 2, designates the prong-bar, and 3, indicates the prongs, the said prong-bar and prongs are desirably

made integral and preferably stamped out from sheet iron or other suitable material.

As hereinbefore referred to, the frame 1, consists of the guards 12, and the guard bar 5, on which the free ends of the prongs 3, rest when the buckle is in use, and the strap bar 6, the two end pieces 7, having enlargements 9, thereon provided with recesses 8, upon the inner faces thereof and about the longitudinal centers thereof, in which recesses the pointed or journaled ends 8', of the prong-bar 2, have their bearings.

Upon Fig. 1, I have shown in full lines the guards 12, turned over upon the said guard bar 5, ready for use, the prongs 3, in full and dotted lines in part under and behind said guards.

In Fig. 2 of the drawings, I have illustrated the said guards 12, in dotted lines turned over upon the guard bar 5; and I have also shown the said guards 12, in full lines before being turned over upon the said guard bar 5.

The guard bar 5, and the strap bar 6, preferably lie in the same plane and parallel with each other. The two end pieces 7, are parallel to each other, the buckle frame being rectangular in form.

The two end pieces 7, are turned at an angle to the upper surfaces of the guard bar 5, and strap bar 6, the lower edge of said end pieces 7, of the frame 1, being upon the same plane with the upper surfaces of the said guard bar and strap bar and the upper edges of the said end pieces projecting above the upper surfaces of the said guard bar and strap bar.

About midway of the said two end pieces 7, are the said enlargements 9, having recesses 8 therein, as hereinbefore referred to in which the ends of the prong-bar 2, are journaled.

The inner edges of the guards 12, as shown at 13, are inclined or beveled in order that the ends of the prongs 3, pointedly inclined at 14, upon slight pressure being made thereon may be sprung inwardly and pass under and behind the inner ends of the guards 12, and the prongs are held therein by the said guards thereby preventing the prongs from pricking the person of the wearer or the operator of the buckle and from piercing and tearing the garments adjacent to and lying in contact with the buckle.

When it is desired that the prongs 3 be retained under the edges 13 of the guards 12 slight pressure of the fingers of the operator

upon the front of the prong 3 is all that is necessary in order that the said prongs be inserted under the guards. When it is desirable to remove the said prongs 3 from under the edges 13 of the guards 12 pressure upon the under side of the prongs accompanied with a gentle springing together of the ends of the prongs will readily remove the prongs from under the edges 13 of the guards 12.

10 My improved buckle is adapted to various uses and can be economically applied to harness as well as to wearing apparel or to any other uses to which buckles in general are applicable.

15 From the foregoing description, taken in connection with the accompanying drawings it is thought that the construction, mode of operation and advantages of the invention will be readily apparent without requiring an extended explanation.

20 Various changes in the form, proportion and minor details of construction may be resorted to without departing from the principle or sacrificing any of the advantages of

this invention and I therefore reserve to myself the right to make such changes as fairly fall within the scope of the appended claim.

It is obvious that many variations in the details of construction would readily suggest themselves to persons skilled in the art, and still be within the spirit and scope of my improvement.

What I do claim as my invention, and desire to secure by Letters Patent, is—

A buckle comprising a pronged bar and a frame to which said bar is pivoted and provided with turned-over guards for the pointed ends of the prongs, said guards having beveled edges to engage the edges of the said prongs when pressure is applied to said prongs to operate the buckle.

In testimony whereof, I have signed my name to this specification in the presence of two subscribing witnesses.

BERNADOTTE BIXBY.
